UNITED STATES PATENT OFFICE.

DERMOT DONELAN, OF LONDON, ENGLAND.

REMEMBRANCER.

1,262,466.

Specification of Letters Patent.

Patented Apr. 9, 1918.

Application filed April 21, 1917. Serial No. 163,679.

To all whom it may concern:

Be it known that I, DERMOT DONELAN, a subject of the King of Great Britain, residing at London, England, have invented 5 certain new and useful Improvements in Remembrancers, of which the following is a specification.

This invention relates to remembrancers or devices for preventing the misplacement 10 and loss of fountain pens, pencils or other articles usually carried in the pocket or on the person.

The object of the invention is to remind 15 the owner of a fountain pen or other article, by means of an audible or other signal, when the article has not been replaced in the pocket after use and the owner moves away from the position in which the article has been used.

20 According to the invention the pocket case for the fountain pen or other article to be safe guarded is provided with mechanism for producing audible or other signals, which mechanism is controlled by the insertion 25 and withdrawal of a pen or other article in such a manner that while the pen is replaced in the case the signal mechanism is restrained from operating, but so long as the case is empty the signal mechanism is 30 in a condition to be operated by the movement or vibration of the wearer. Thus, if the wearer omits to replace a fountain pen in its case after use and begins to walk away, the signal mechanism is operated immediately 35 and the wearer is reminded of the misplaced pen.

The invention is applicable for use on a motor car or other vehicle subject to vibration, in which case a larger device could be 40 made than that intended to be carried in the pocket.

In the accompanying drawings:

Figure 1 is an elevation of one form of device the casing being in section, so as to disclose 45 the internal mechanism.

Fig. 2 is a plan corresponding to Fig. 1.

Fig. 3 is a side view partly in section illustrating another form of device.

Fig. 4 being a plan.

50 Figs. 5 and 6 are elevations partly in section and a plan illustrating a further form of the invention.

Fig. 7 is an elevation partly in section illustrating a still further form.

55 In carrying out the invention according to one form suitable for example as a pocket

case for holding a fountain pen, and as illustrated by Figs. 1 and 2, the case 1 is fitted with a bell 2 and with a pendulum, hammer or striker 3 which is adapted to 60 oscillate whenever the wearer walks, in a similar manner to the action of the operating pendulum of a pedometer. The head 4 of the striker may comprise a steel or other casing filled with lead. The striker 65 is pivoted at 5 and has a somewhat flexible arm 6 adapted to engage with a stop 7 which may be adjustable. A spring 8 is secured at one end to the striker 3 and at the other end to a screw 9 adjustable in a bracket 10 70 by a milled nut 11, the screw having a flat on it to prevent its rotation in the bracket which has a corresponding bore to receive it, permitting the screw to slide therein when the nut is rotated.

75 A pawl 12 is pivoted conveniently on the bell pillar 13, and has one end 14 held in frictional contact with the head 4 by a spring 15, so long as chains 16, 17, are slack, thereby preventing oscillation of the striker. 80 The head 4 may be provided with a notch or teeth to receive the end 14 to hold the head in an inoperative position. The chains 16, 17, connect the upper end of the pawl 12 to spring holders 18, 19, for a fountain pen 85 20 and a plug 21 respectively. The plug 21 may be connected by a cord 22 to a pair of spectacles or any other article usually carried on the person and apt to be mislaid.

90 The holders 18, 19, each have one side fixed to the casing 1 by brazing, riveting or otherwise, while the other side to which the chain 16 or 17 is connected is free to move under its own elasticity. The arrangement is such that when the pen 20 and plug 95 21 are in the holders the springy sides of the holders are forced away from the fixed sides and the chains 16, 17, are slackened, but when either the pen 20 or the plug 21 is removed, the respective holder contracts and 100 tightens the corresponding chain 16 or 17, moves the pawl 12 about its pivot and disengages the end 14 of the pawl 12 from the head 4 of the striker. So long as the wearer is still the signal does not operate, but 105 should the wearer move away without replacing the pen or plug, as the case may be, the striker immediately oscillates and striking the bell 2 produces an audible signal to remind the wearer to replace the pen 110 or plug.

It will be understood that any desired

number of holders such as 19 may be provided according to the size of the apparatus, the plugs for the various holders being connected to the articles to be safeguarded 5 by cords, chains or in any other convenient way, or the supplementary holders may be shaped so as to receive the articles as in the case of the pen.

In the form shown in Figs. 3 and 4 the 10 pen 20 is carried in a clip 25 outside the casing 1, and is connected by a cord 22 to one of a series of plugs 21, there being six holders 19 for plugs 21 representing various articles to be remembered to which the plugs 15 are connected by cords 22. All the plugs are connected by cords or chains 17 to the pawl 12 controlling the signal mechanism.

In the form illustrated by Figs. 5 and 6, a bent steel strip 26 is adopted in place of a 20 bell to emit the audible signal, the end 27 of the strip being secured to the casing 1 and the remainder of the strip being free so that when a projection 28 is struck by the hammer 4 of the vibrating element the 25 strip will vibrate somewhat like a tuning fork. The vibrating element comprises parallel links 3, 3, pivoted at 5, 5, to the casing 1, and at 29, 29, to the hammer 4. A wire spring 8 has one arm 30 embracing one of 30 the links 3, is wound around one of the pivots 5, and has another arm 31 abutting against a pin 32. The strip 26 acts as a holder for the pen 20. When the pen is inserted it presses back a spring 33 which engages with a pin 34 on the upper pair of 35 links 3, and arrests motion thereof and therefore of the hammer 4, and when the pen is withdrawn the spring 33 moves away from the pin 34 and so leaves the links 3 40 and therefore the vibrating element free to oscillate.

In the form shown in Fig. 7 a helically coiled metal strip 35 is adopted in place of the strip 26. In this form the parts are 45 similarly lettered to the corresponding parts in Figs. 5 and 6. The spring 33 has a pin 36 which engages with the lower pair of links 3, when the pen is inserted and recedes from said links when the pen is withdrawn. Otherwise the action is similar to 50 that of the last mentioned form of the invention. It is to be understood that the strips 26 and 35 are the equivalents to the bell 2 as regards sound emitting means and the term "bell" used in the claims is to be 55 used in this sense.

I claim:—

1. A remembrancer comprising a casing

fitted with means for engaging an article inserted in said casing, and a signaling device adapted to be operated by vibration of said casing, said article engaging means being adapted to arrest and to release said signaling device accordingly as an article is inserted in and removed from the casing, 65 substantially as and for the purpose hereinbefore set forth.

2. A remembrancer comprising a casing, means in the casing for engaging an article inserted therein and signaling means comprising an audible signal and a striker adapted to be oscillated by vibration of said casing, said article engaging means being adapted to arrest and to release said striker when an article is inserted in and removed 75 therefrom, substantially as and for the purpose hereinbefore set forth.

3. A remembrancer comprising a casing for receiving a pen, said casing being fitted with an audible signaling device, and an 80 element for operating same, means for arresting and releasing said element, said arresting and releasing means being adapted to be operated by the insertion and withdrawal of an article in and from said casing, 85 substantially as and for the purpose hereinbefore set forth.

4. A remembrancer comprising a casing, an audible signaling device in the casing, an 90 element for striking the signaling device, means for arresting and releasing said element, said arresting and releasing means being operable by the insertion and withdrawal of an article in and from the casing, 95 substantially as and for the purpose hereinbefore set forth.

5. A remembrancer comprising a casing, said casing being fitted with a signaling element adapted to form also a holder for a pen, a vibrating element comprising parallel links, and a hammer for striking the signaling element, and means for arresting and releasing said vibrating element, said arresting and releasing means being operable by the insertion and withdrawal of a 100 pen in and from said holder, substantially as and for the purpose hereinbefore set forth.

In testimony whereof I have signed my name to this specification in the presence of 110 two subscribing witnesses.

DERMOT DONELAN.
